UNITED STATES PATENT OFFICE

ADOLPH C. KLOPPING, OF TOLEDO, OHIO

LEVER GRIP

Application filed June 23, 1930. Serial No. 463,164.

This invention relates primarily to control levers, such for instance as hand operated brake and gear-shift levers of automobiles, and particularly to the provision of an enclosing cap adapted for use on the hand grip portion of such levers of the stamped type.

The object of my invention is the provision of an attachment for control levers, particularly of the stamped type, to provide a finished grip therefor and to cover up seams and other unsightly portions customarily present on the handles of levers of this type.

The invention is fully described in the following specification, and while in its broader aspect it is capable of embodiment in different forms, two embodiments thereof are illustrated in the accompanying drawings, in which—

20 Figure 1 is a side elevation of a lever of the stamped type equipped with the hand grip embodying the invention, with the hand grip and associated portion of the lever in central vertical section; Fig. 2 is a side elevation of the upper end portion of the lever with the grip remover; Fig. 3 is a front elevation of the lever with the grip in position thereon; Fig. 4 is a perspective view of the grip centering button used in connection with one form of the invention; Fig. 5 is a view similar to Fig. 1 with slightly modified form of grip centering means; Fig. 6 is a view similar to Fig. 5 with the upper end portion of the lever in full and with the hand grip removed; and Fig. 7 is a perspective view of a grip centering button used in connection with the form shown in Fig. 5.

Referring to the drawings, 1 represents an emergency brake lever formed of a single piece of sheet steel with its handle portion 2 shaped in cylindrical form and customarily having a seam lengthwise thereof where the two side edges of the metal are brought together in abutting relation. In the form of the invention shown in Figs. 1 and 2, the upper end of the handle 2 is left open to receive the stud portion of a grip centering button 3.

The hand-grip 4 which, in cooperation with the lever handle and centering button,

embodies my invention, is preferably drawn in socket form from sheet metal so as to be free from seams and is of a length to suit the length of the lever handle to which it is to be applied. The grip 4 is preferably tapered 55 from its outer closed end inwardly to its open end with the opening at its inner end conforming in size and cross-sectional shape to the cross-sectional shape of the lever handle 2 so that it can be slipped down over said handle and snugly fit the same at least at its inner end.

In order to firmly hold the grip 4 on the lever handle, the grip is provided at its inner end in the present instance with an integral inwardly pressed tongue 5 which enters a recess or opening 6 in the inner end portion of the handle 2 when the grip is in assembled position thereon. The projection of the tongue 5 is such that when it is disposed in the recess 6, its free end coacts with the outer or upper wall of such recess to prevent withdrawal of the grip from the lever.

In order to fix the outer enlarged end portion of the grip 4 in centered relation to the handle 2, a centering button 3 of flanged form is provided in the outer closed end portion of the grip 4 with its flange fitting the interior of the grip at its enlarged outer end portion and the stud portion of the button entering the open outer end of the lever handle 2 and snugly fitting the same. It will be understood that the button 3 is assembled in the grip 4 before the grip has been drawn down to the tapered form shown. With the flange of the button 3 fitting the enlarged outer end portion of the grip 4 and the stud of such button fitting the open end of the lever handle, it is apparent that the grip is firmly 90 centered at its outer end with respect to the handle.

In Figs. 5 and 6, the outer end of the lever handle, which in this case is designated 2^a, is shown as being drawn down to form an axially projecting stud 7 instead of being of the open form shown in Figs. 1 and 2, and the centering button 8 is of disk form of a size to fit the enlarged closed end portion of the grip 4 and is provided with a central opening 9 for 100

snugly receiving the stud 7 on the handle end when the grip is forced home thereon.

It is apparent that I have provided a simple form of grip for use on the handles of 5 stamped levers to give such handles a finished and pleasing appearance and that such grip may be easily and quickly applied to a lever and secured thereto in rigid centered relation.

I wish it understood that my invention is 10 not limited to any specific construction, arrangement or form of the parts, as it is capable of different modifications without departing from the spirit of the claims.

Having thus described my invention, what 15 I claim as new and desire to secure by U. S. Letters Patent is:

1. In combination, a lever, a socketed hand grip telescoped over the handle portion of the lever, means for retaining the grip on 20 the lever handle, and means interiorly of the grip for interengagement with the outer end portion of the handle to center the outer end of the grip relative to the handle.

2. In combination, a lever, a socketed hand 25 grip telescoped over the handle of the lever, said grip being interiorly tapered from its outer closed end toward its open end, means interconnecting the outer end of the handle and the interior of the grip at its enlarged 30 closed end to center such end of the grip with respect to the handle, and interconnecting means between the open end portion of the grip and the handle to retain them in assembled relation.

3. In combination, a stamped lever having 35 a cylindrical handle portion with a side recess therein, a sheet metal grip of elongated socket form tapered from its outer closed end inwardly to reduce the size of the grip at its inner end, said grip being telescoped over 40 said handle and having its open end fitting the handle and its outer end larger than the handle, said grip having an integral tongue which enters the recess of the handle to retain the grip and handle in assembled relation, and means interiorly of the closed end 45 of the grip coacting with the outer end of the handle to firmly center the outer end of the grip relative to the handle.

4. In combination, a lever, a socketed hand- 50 grip telescoped over the handle portion of the lever, and means interiorly of the grip interengaging with and firmly centered by the outer end portion of the handle and 55 co-acting with the grip to center it with respect to the handle.

5. In combination, a lever, a socketed hand- 60 grip telescoped over the lever handle and having its inner end fitting the handle and 65 its outer end loose with respect to the handle to permit lateral rocking movements of one on the other, and means interiorly of the grip and having holding engagement with both the grip and handle to prevent 70 said lateral rocking movements.

6. In combination, a lever having a longitudinally extending hole in the outer end of its handle, a socketed hand-grip telescoped over the handle of the lever and having its outer end loose on the handle to permit relative rocking movements thereof, and a button in centered engagement with the outer end portion of the grip and having a part entering said hole in the handle and co-operating with the lever handle to firmly hold the grip against lateral movement relative thereto.

7. In combination, a lever having its handle end provided with a longitudinally projecting stud, a socketed hand-grip telescoped over the handle of the lever and having its outer end loose on the handle to permit relative rocking movements thereof, and a button interiorly of the grip in centered engagement with the outer end portion thereof and having an opening receiving the handle stud and cooperating with it to firmly hold the grip against lateral movements relative to the handle.

In testimony whereof I have hereunto 90 signed my name to this specification.

ADOLPH C. KLOPPING.
